(57) CLAIM

The design for trailing end of a spinal implant, substantially as shown and described.

DESCRIPTION

FIG. 1 is a perspective view of the trailing end of a spinal implant in accordance with the first embodiment of my claimed design with the remainder of the implant shown in hidden line and forming no part of the claimed design;

FIG. 2 is an end view of FIG. 1;

FIG. 3 is a side elevational view of FIG. 1 with the remainder of the implant shown in hidden line and forming no part of the claimed design;

FIG. 4 is a perspective view of the trailing end of a spinal implant in accordance with a second embodiment of my claimed design with the remainder of the implant shown in hidden line and forming no part of the claimed design;

FIG. 5 is an end view of FIG. 4; and,

FIG. 6 is a side elevational view of FIG. 4 with the remainder of the implant shown in hidden line and forming no part of the claimed design.
